UNITED STATES PATENT OFFICE.

WILLIAM R. KENWARD, OF AXTELL, KANSAS.

HUSKING-MACHINE.

1,118,936.

Specification of Letters Patent.

Patented Dec. 1, 1914.

Application filed September 30, 1913. Serial No. 792,655.

To all whom it may concern:

Be it known that I, WILLIAM R. KENWARD, a citizen of the United States, residing at Axtell, in the county of Marshall and State of Kansas, have invented a new and useful Husking-Machine, of which the following is a specification.

This invention relates to husking machines, it being more particularly an attachment adapted to be placed on a wagon or other vehicle, means being provided whereby the husking mechanism can be driven by one or more wheels of the vehicle to which the structure is attached.

A further object is to provide improved means for husking the corn, said means including a novel arrangement of husking rolls and means for conveying the ears positively along the rolls so as to discharge them ultimately into an elevator provided therefor.

A further object is to provide means for collecting the loose grains of corn and directing them into the elevator so that they will be discharged into the vehicle with the ears of corn.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is an elevation of one side of the apparatus applied to a wagon. Fig. 2 is an elevation of the opposite side of the apparatus. Fig. 3 is a rear elevation, parts being broken away. Fig. 4 is an enlarged end elevation of the husking rolls. Fig. 5 is a plan view of one of the husking rolls and a portion of the conveyer combined therewith. Fig. 6 is an end elevation of the husking rolls and showing a modified means for actuating the same. Fig. 7 is a diagrammatical end elevation showing a modification. Fig. 8 is a side elevation showing a part of the structure depicted in Fig. 7. Fig. 9 is a fragmental top plan showing a portion of the roll-driving mechanism.

Referring to the figures by characters of reference A designates the body or box of a vehicle having the usual supporting wheels B. A sprocket 1 is adapted to be bolted or otherwise secured to the inner side of one of the wheels B while another sprocket 2 is adapted to be secured to the inner side of the other wheel B. Secured to the running gear of the vehicle in any suitable manner, are side frame members 3, preferably U-shaped, the lower arms of the frame members being shown extended under the body A while the upper arms are extended along the sides of the body, both arms being attached to the body by suitable straps 4 extended under the body and across the frame members and then hooked into engagement with the upper edges of the sides of the body A. This structure has been clearly shown in Fig. 3.

The two frame members 3 carry the mechanism constituting the present invention. These frame members are connected, back of the body A, by a cross beam 5 on the end portions of which are journaled vertical shafts 6 and 7 respectively, each of these shafts carrying a sprocket 8 and the two sprockets being engaged by an endless conveyer belt 9 which can be in the form of a chain, there being outstanding fingers 10 upon the conveyer belt at distances apart slightly greater than the length of the ears of corn to be acted upon. The flights of the conveyer extend transversely of the machine and back of the body A, the forward flight being close to and parallel with a husking roll 11 mounted in bearings 12 supported by the frame members 3.

The fingers on the forward flight of the conveyer extend over the husking roll 11, as shown in Figs. 1 and 2 and the husking roll 11 is provided either with longitudinal corrugations or with spiral ribs, as preferred, this roller receiving motion from intermeshing pinions 11^a, one of which is mounted on the shaft of the roll 11, the other of which (see Fig. 9) is carried by a shaft 100 supported in any appropriate manner upon the frame of the machine, the shaft 100 having a sprocket wheel 18 receiving a chain 17. The chain 17 extends forwardly along one side of the body A and is mounted, at its front portion, upon a sprocket 19 carried by the short arm 20 of a bell crank lever 21, the long arm of this lever being extended upwardly beyond the side of the body A so

- as to be manipulated conveniently. This long arm of lever 21 can be locked in any suitable manner so as to be held against movement and when sprocket 19 is in its 5 lowermost position, the lower flight of chain 17 is held in engagement with the upper portion of sprocket 1 so that, as the wheel B rotates, the chain 17 will be actuated and motion thus transmitted to the roller 11.
- 10 The roller 11 drives a second roller 13 which is journaled in bearing blocks 14 slidably mounted in guides 15. The surface of roller 13 is formed of rubber or other suitable soft material designed to frictionally engage the roller 11 and springs 16 bear against the blocks 14 so as to press roller 13 yieldingly against roller 11 at all times. The roller 11 therefore constitutes the means for driving the roller 13 and in 15 turn is adapted to be driven by the chain 17 which engages the sprocket 18 secured to the shaft 100. Another roller 22 is supported above and normally contacts with the roller 13, this roller 22 being journaled 20 in bearings 23 carried by supporting springs 24, the springs being so arranged as to press roller 22 yieldingly against roller 13. Roller 22 is preferably provided with a soft periphery made up of rubber or other suitable 25 material designed to frictionally engage roller 13 so that, during the rotation of said roller 13, the roller 22 will be actuated. The direction of rotation of the various rollers 30 has been indicated by arrows in Fig. 4. An arcuate shield 25 is arranged to bridge the space between the rollers 22 and 11, there being a sufficient space between this shield 25 and roller 11 to receive the fingers 10 of the conveyer 9.
- 35 40 A trough 26 is supported under the rollers 11, 13 and 22, this trough being inclined downwardly toward one side of the machine and being provided, at its top, with a grate 27 on which the husks and any loose grains 45 of corn are adapted to fall from the rollers of the husking mechanism. The grate is so inclined that the husks will slide therefrom and onto the ground back of the machine while the loose grains of corn will drop between the bars of the grate and into the trough. The trough is inclined downwardly so as to discharge into the lower end 50 of an elevator casing 28 supported at one side of the apparatus, there being an endless 55 elevator 29 within this casing 28. Said elevator has cleats 30 thereon for engaging material discharged through this casing 28 and causing the material to move upwardly to an outlet spout 31 which extends from the 60 upper end of the casing 28 and discharge into the body A. Another spout 32 extends from under the rollers 11, 13 and 22 at one end and serves to direct the ears of corn from the ends of the rollers into the elevator casing 28. Thus it will be seen that the ele-

vator 29 serves not only to lift the loose grains of corn up to the spout 31 but also to lift the husked ears to said spout. The elevator 29 is driven by novel mechanism provided for that purpose. The said mechanism includes a shaft 33 on which the elevator 29 is mounted, this shaft being provided with a gear 34 constantly meshing with another smaller gear 35 secured to a shaft 36. Said shaft 36 has a sprocket 37 secured thereto and engaging the sprocket is a drive chain 38 engaging a sprocket 39 carried by a bell crank lever 40. One arm of this bell crank lever is connected by a rod 41 to a shifting lever 42 fulcrumed upon one side of the body A, any suitable means being provided for locking this lever against movement. It will be apparent that when the shifting lever is moved in one direction, sprocket 39 will be shifted downwardly, thus bringing the lower flight of chain 38 into engagement with the sprocket 2 so that, as the vehicle moves forward, motion will be transmitted from sprocket 2 to chain 38 and thence to shaft 36 and, through gears 35 and 34 to shaft 33 and elevator 29. By shifting lever 42 in the opposite direction, however, the chain 38 is lifted out of engagement with the sprocket 2 and the operation of the elevator is thus stopped.

45 A sprocket 43 rotates with shaft 33 and is engaged by a chain 44 which, in turn, engages a sprocket 45 secured to a shaft 46 which is journaled in one of the frame members 3. This shaft 46 has a bevel gear 47 which meshes with another bevel gear 48 secured to the lower end of shaft 7. Thus it will be seen that as long as the elevator 29 is in operation, motion will be transmitted to the conveyer 9 which receives its motion from the shaft 7.

50 In order that the husking rolls may be properly supplied with ears for husking, a delivery spout 46' is fixedly mounted on one of the frame members 3 and extends upwardly and laterally therefrom. A transverse shaft is extended laterally from this spout, as shown at 47' and has a sprocket 48' secured to it and receiving motion through a chain 49, from a sprocket 50 which rotates with the shaft 100. Shaft 47' has an elevator casing 51 hung therefrom and mounted in this casing is an elevator 52 extending downwardly and forwardly. The lower end of the elevator casing is supported by a lifting rod 53 connected, as by means of a link 54, to one arm 55 of a bell crank lever 56, the other arm of the bell crank lever being extended above the body A and provided with any suitable means whereby it can be locked against movement. Obviously by means of this lever 56 the lower end of the elevator casing can be swung upwardly or downwardly so as to be brought to any desired distance.

from the ground. Arranged along the outer side of the elevator casing 51 are snapping rolls 57 and 58, respectively, the roll 58 being nearest the elevator 52 while the roll 57, which is most remote from the elevator 52, is elevated above the roll 58, as will be apparent by referring to Figs. 1 and 3. That portion of the elevator casing 51 at one side of the rolls 57 and 58 is cut away so that the corn when snapped from the stalk will be free to fall laterally from the rolls and onto the elevator 52. Gathering fingers 60 diverge from the lower ends of the rollers, as shown in Fig. 3 and operate as ordinarily to collect the stalks so that they will be fed into the pass between the snapping rolls 57 and 58. The two snapping rolls rotate in opposite directions, this being due to the fact that each of them has a gear 61 at its upper end, the two gears meshing. One of the snapping rolls 58, has a shaft 62 extending upwardly therefrom and provided with a bevel gear 63 which meshes with a gear 64 secured to shaft 47. From the foregoing description it will be apparent that when the machine is drawn forward and the chains 17 and 38 are in engagement with their respective driving sprockets, motion will be transmitted to the various parts of the mechanism. Thus the stalks will be directed into the pass between the snapping rolls 57 and 58 and these rolls, which can be either corrugated, plain, or formed with spiral ribs, will engage the stalks and break the ears therefrom. The ears will be shifted laterally by the rolls 57 and 58 so as to fall onto the elevator 52 which elevator will carry them upwardly and discharge them into the spout 46' and this spout, in turn, will direct the ears onto the feeding ends of the husking rolls. The rolls 11 and 13 will coöperate to remove the husks from the ears and direct the husks downwardly onto the grate 27. During this action of the rolls 11 and 13 the fingers on the conveyer 9 will engage the ears and drag them longitudinally of the rolls, the rotating roll 22 serving to maintain the ears in position between the fingers 10 on the conveyer. When the ears reach the discharge ends of the husking rolls they are directed into the spout 32 and thence onto the elevator 29 which carries them to the wagon body in the manner hereinbefore described. It has been found that by providing a conveyer in connection with husking rolls such as disclosed, the operation of removing the husk is more efficiently performed than where the ears are shifted along the rolls solely by gravity. Furthermore by utilizing one husking roll which is operated solely by frictional engagement with the other husking roll, the first named roll is free to stop rotating should the ears become wedged between the rolls and, consequently, danger of

crushing the ears is reduced to the minimum.

Instead of driving the husking rolls in the manner hereinbefore described and as illustrated in Fig. 4, mechanism such as 70 illustrated in Fig. 6 can be utilized. By referring to this figure it will be seen that a husking roll 61 is driven as before described, and frictionally engages the husking roll 62. This husking roll is driven frictionally in 75 the manner hereinbefore described but a worm 63 rotates therewith and constantly meshes with a worm gear 64 secured to a shaft 65. This shaft is journaled on an arm 66 which is fulcrumed on the shaft 67 of roller 62 and a bevel gear 68 rotates with shaft 65 and meshes with another bevel gear 69 secured to a shaft 70 journaled in the arm 66. A sprocket 71 rotates with shaft 70 and transmits motion through a chain 72 80 to a sprocket 73 which is connected to the roll 74, said roll being journaled in an arm 75 formed integral with or fixedly connected to the arm 66. Thus it will be seen that by shifting arm 75 the roll 74 can be adjusted 85 toward or from the roller 61 without, however, disturbing the mechanism employed for transmitting motion from roll 62 to the roll 63. In this modified form a shield 76 similar to the shield 25 is extended from 90 the arm 75 so as to bridge the space between the rollers 61 and 73.

Importance is attached to the fact that the mechanism herein described can be applied readily to a wagon already in use and by 100 drawing the wagon along one side of a row, the corn growing in the row will be quickly and efficiently gathered and husked, the husks being discharged onto the ground and the ears directed into the body of the wagon. 105

It is to be understood that the roller 22 shown in Fig. 4, can be adjustably mounted on the spring 24 by providing longitudinal slots 24' in which the bolts 23', which secure bearings 23 to the springs 24, can be adjustably mounted. 110

By referring to the drawings it will be seen that the husking rolls 11 and 13 form the bottom of a trough the sides of which are made up of the roll 22 and the conveyer 115 9 respectively.

In Figs. 7 and 8 the parts remain as shown in Fig. 6, corresponding parts being designated by the same numerals with the suffix "a." In this form of the invention, a spiral 120 roller 101 formed in one or more sections and supported in any convenient manner upon the frame work of the machine, coacts with the ear of corn E to advance the same longitudinally of the rolls 74^a, 62^a, and 61^a. 125

The roller 13, being covered by a facing of rubber or the like, gives a cushioning grip on the husk, when used in connection with the corrugated roller 11.

Attention is called to the fact that the 130

shield which bridges the space over the husking rolls 11 and 13 is for the purpose of preventing the ears of corn from being thrown upwardly away from the husking rolls while the rolls are stripping the husks from the ears of corn. In other words the ears of corn are held down on the husking rolls and the ears are caused to rotate while being moved longitudinally, this rotation being facilitated by roll 22 so that all of the husks will be removed from the ears. The ears are under absolute control at all times while being conveyed along the husking rolls.

15. What is claimed is:—

1. A husking machine including a receptacle for husked corn, an elevator at each side of the receptacle, and husking mechanism extended between the elevators, one of 20 said elevators constituting means for elevating ears to the husking mechanism and the other elevator constituting means for conveying husked ears to the receptacle, the husking mechanism and the elevators being 25 supported by the receptacle.

2. The combination with coöperating husking rolls, and means for supplying ears thereto, of an upper roll, a shield overlying and bridging the space between the rolls, a 30 conveyer extending between the rolls and the shield for directing ears longitudinally of the rolls during the operation of the rolls,

said upper roll constituting means for throwing the ears toward the conveyer.

3. The combination with coöperating 35 husking rolls, means for holding one of said rolls yieldingly in contact with the other roll to drive it, and an upper roll parallel with the husking rolls, of an endless conveyer for engaging the ears resting on the 40 husking rolls and to carry them longitudinally of the rolls, said upper roll constituting means for directing the ears being husked into engagement with the conveying means, and a shield overlying and bridging 45 the space between the upper roll and the conveying means.

4. In mechanism of the class described, the combination with coöperating frictionally engaging husking rolls, and means for driving one of the rolls, of an upper roll parallel with said husking rolls and adjustable relative thereto, an endless conveyer having outstanding fingers projecting over 50 one of the husking rolls, and a shield overlying and bridging the space between said conveyer and the upper roll.

In testimony that I claim the foregoing as my own, I have hereto affixed my signature in the presence of two witnesses.

WILLIAM R. KENWARD.
